DISCHARGING MAGAZINE AND HOLDER

Francis C. Worth, Brooklyn, N. Y.

Application December 5, 1947, Serial No. 789,782

10 Claims. (Cl. 312—70)

1

This invention relates to novel and useful improvements in a device for retaining and dispensing a plurality of articles.

An object of this invention is to retain a plurality of articles, preferably flat, and dispense a selected number of these retained articles.

Another purpose of this invention is to retain the articles by exerting a pressure along the edges thereof and relieve this pressure for a duration thereby permitting at least one article to drop from the stack.

Another purpose of this invention is to simultaneously move a pair of plates which are positioned beneath the articles in order to permit the lowermost article or articles to be dispensed and to relieve the pressure exerted on the edges of the articles.

Another purpose of this invention is to regulate the travel of the article edge engaging means selectively and controllably in accordance with the travel of the base plates for supporting the articles.

Another purpose of this invention is to provide improved means for carrying out all of the above-mentioned functions.

Another purpose of this invention is to resiliently bias a panel against the edges of the articles to be dispensed and to adjustably support the said panel so that it may be selectively raised and lowered in order to dispense selected quantities of articles.

Another purpose of this invention is to provide an improved and simplified device which efficiently dispenses either a single sheet or a plurality of sheets of a preferably flat material.

Other objects and features of novelty will become apparent to those skilled in the art, in following the description of the preferred form of the invention, illustrated in the accompanying drawings, wherein:

Figure 1 is a plan view of the preferred form of the invention;

Figure 2 is a sectional view of the invention shown in Figure 1;

Figure 3 is an enlarged sectional detail construction illustrating the adjustable supporting means for the panel;

Figure 4 is an end view of the device shown in Figure 1;

Figure 5 is an end view of the device shown in Figure 1, illustrating the end opposite that illustrated in Figure 4;

Figure 6 is a bottom plan view of the device illustrated in Figure 1;

Figure 7 is an enlarged sectional view taken substantially on the line 7—7 of Figure 6 and in the direction of the arrows;

Figure 8 is a sectional view illustrating certain details of construction; and;

Figure 9 is a longitudinal sectional view taken

2

substantially on the line 9—9 of Figure 2 and in the direction of the arrows.

Serious difficulty was encountered in dispensing a plurality of sheet articles or units such as cards, paper, flat cartons or slabs of any material suitable for handling in the manner to be described.

Illustrated and described herewith is a means for handling (retaining and discharging) either a single sheet or a plurality of sheets of material in accordance with minor adjustments made to a relatively simple apparatus.

The general mode of operation of the invention is to retain a stack of sheets of any suitable article by means of engaging the edges thereof. A selected portion of the engaging means may be vertically adjusted in order to permit either one or a plurality of articles to be dropped from the mechanism thereby dispensing the same under certain predetermined conditions.

These conditions are as follows: A pair of plates are pivoted beneath the article retaining means and on these plates the said articles are seated. Means for urging the plates in divergent fashion is provided whereby the bottom articles may be dropped even from these plates. There is provided means for interconnecting the plates with the article retaining means, whereby the articles may be released at a selected portion of the cycle of operation of the plates. Then, the retaining means is again returned to the article engaging position leaving either a single or a few sheets free of the clamping action of the article engaging means. It is these free articles which are dispensed.

A support generally indicated at 10 is provided of any suitable material and is utilized as a recipient for various operative elements of the invention. This support is composed of a base including a pair of substantially parallel rails 12 and 14 respectively and a pair of cross members 16 and 18. A relatively stationary wall 20 is attached to the said cross member 16 for cooperation with another wall in retaining the articles to be dispensed therebetween.

A frame generally indicated at 22 is supplied for the cooperation between the wall 20 and the said frame comprises a pair of legs 24 and 26 respectively which are attached to the said cross member 18 by any suitable, conventional means. A header 28 connects the said legs 24 and 26 and has an aperture therein.

A panel 30 having an arcuate bottom edge 32 is supplied in the said frame 22 and is supported to the said header 28. The means for supporting the said panel may be seen particularly well in Figure 3 wherein there is disclosed a threaded shaft 34 anchored at one end to the said panel 30 and extending through the aperture in the said header 28. A conventional nut 36 is supplied on

the end of the said shaft 34 which when selectively tightened and loosened forms means for regulating the height of the panel relative to the base 10.

Means for resiliently biasing the said panel 30 in a selected direction is provided. This means may be seen particularly well in Figure 1 wherein there is disclosed a conventional leaf spring 38 anchored to the said panel 30 and having the ends thereof engaging the arms 24 and 26 respectively. It is readily apparent that by this construction the said panel 30 is constantly urged in a single direction, and a spring 33 is seated on the panel 30 for biasing the header and panel relative to each other.

A pair of plates are provided beneath the said cross members 16 and 18 and are pivoted thereto. These plates 42 and 44 respectively are pivoted at their opposite ends, the plate 42 being pivoted by means of the conventional pivot pin 46 while the plate 44 is pivoted by means of the pivot pin 48.

Reference now to Figure 2 discloses that the said plates 42 and 44 form a seat for the stack of articles maintained between the wall 20 and panel 30.

Manually operable means is provided for moving said plates 42 and 44 away from each other. This means may be noted as the simplified linkage illustrated in Figure 6 and consisting of the following structure: A bar 50 is provided beneath the said base 10 and a link 52 is pivoted thereto. This link is also pivoted by means of the pin 54 to the said cross member 16. The terminal portion of the said link 52 is then pivotally associated with the said plate 44 through the medium of another conventional pin 56.

Another link 58 is supplied at the terminal portion of the actuator rod 59 by means of a pivotal connection at 60. This link 58 is pivoted to the plate 42 by means of a pivot pin 62 while the end of the said link 58 is pivotally anchored at 66 to the said cross member 18. Following the arrows indicating direction of travel in Figure 6, it will be appreciated that upon movement of the actuator rod 59 in a single direction the plate 42 will be urged pivotally in the same direction while the plate 44 will be urged pivotally in a direction opposite from that of plate 42. It may now be seen that if any articles are freely supported on the said plates 42 and 44 respectively actuation of the actuator bar 50 in the direction indicated by the arrows will permit the free articles resting thereon to be dropped or dispensed.

Means for interconnecting the travel of the said plates 42 and 44 and the travel of the panel 30 is provided. This means is preferably a plurality of links and consists of a pitman 80 connected with the lever 58 and a second lever 82. This second lever is pivotally associated with the bottom of the said cross member 18 and has a set screw 84 operatively engageable therewith.

The set screw 84 is threadedly received in a bracket 86 which is in turn rigidly secured to the said panel 30. It may now be seen that upon actuation of the links 52 and 58, the plates 42 and 44 respectively will be urged in selected directions and the panel 30 will also be urged against the stack of articles by the force of the spring 38. This operation releases the articles maintained on the plates free of the panel 30 and wall 20 yet retains the remainder of the articles between the panel and wall. Upon actuation of the rod 59 in the opposite direction the panel 30 is moved from the articles to allow a selected number to fall on

the plates 42 and 44 respectively in accordance with the adjusted position of the panel 30.

The number of articles to be dispensed is obviously determined by the distance of the panel 30 from the plane of the two plates 42 and 44 respectively.

In order that the plates 42 and 44 respectively will be free in their travel and not be impeded by engagement with the pivot pins 54 and the pivotal connection between the link 82 and the cross member 18, notches or cutouts 90 are supplied in the said plates to provide clearance. Other obvious and simplified mechanical expedience may obviously be resorted to in connection with the above described structure, without departing from the spirit of the invention. Accordingly, limitation is sought only in accordance with the scope of the following claims.

Having described the invention, what is claimed as new is:

1. A device for retaining and dispensing relatively flat articles comprising a support including a base and a pair of spaced substantially parallel walls for supporting a stack of articles, means attached to one of said walls and said base for dispensing the bottom article of a stack retained between said walls including a first and second plate pivoted to said base beneath said walls, means for moving said plates away from each other and one of said walls toward the other wall to permit the bottom article to drop from between the walls and to retain the remainder of the articles fixed between said walls.

2. A device for retaining and dispensing relatively flat articles comprising a support including a base and a pair of spaced substantially parallel walls for supporting the upper members of a stack of articles, means mounted beneath said walls for supporting and dispensing the bottom article of a stack retained between said walls, said supporting and dispensing means including a first and second plate pivoted to said base beneath said walls, means for moving said plates pivotally and away from each other to permit the bottom article to drop from said plates, a first of said walls being rigidly secured to said base, the second wall including a frame secured to said base, a panel positioned in said frame, adjustable means connecting said plate moving means and said panel for moving said panel toward said first wall when said plates are moved to drop the article disposed thereon.

3. A device for retaining and dispensing relatively flat articles comprising a support including a base and a pair of spaced substantially parallel walls for supporting the upper members of a stack of articles and means for dispensing the bottom article of a stack retained between said walls, said dispensing means including a first and second plate pivoted to said base beneath said walls, means for moving said plates away from each other to permit the bottom article to drop from between the walls, a first of said walls being rigidly secured to said base, the second wall including a frame secured to said base, a panel positioned in said frame, adjustable means for connecting said first plate and said panel to impart movement of said first plate to said panel, means for selectively and adjustably raising and lowering said panel relative to said first plate so that one or more articles will be out of the path of movement of said panel thereby allowing them to be dispensed upon a predetermined movement of said plates.

4. A device for retaining and dispensing rela-

tively flat articles comprising a support including a base and a pair of spaced substantially parallel walls for supporting the upper members of a stack of articles and means for dispensing the bottom article of a stack retained between said walls, said dispensing means including a first and second plate pivoted to said base beneath said walls, means for moving said plates away from each other to permit the bottom article to drop from between the walls, a first of said walls being rigidly secured to said base, the second wall including a frame secured to said base, a panel positioned in said frame, adjustable means connecting said first plate and said panel to impart movement of said first plate to said panel, means for selectively and adjustably raising and lowering said panel relative to said first plate so that one or more articles will be out of the path of movement of said panel thereby allowing them to be dispensed upon predetermined movement of said plates and means secured to said frame for resiliently biasing said panel against the upper members of the stack of articles when said plates are moved away from each other.

5. In an article retaining and dispensing device, a support including a base, a wall secured to said base, and a frame secured to said base spaced from said wall, means associated with said support for maintaining a plurality of articles and dispensing a selected number thereof, said means including a panel with means yieldingly pressing said panel against some of the articles to hold said some of the articles while at least one of the other articles is being discharged, means for supporting said panel within said frame for vertical adjustment, said panel cooperating with said wall to retain the upper members of a stack of articles, plates pivoted to said base for supporting at least the bottom member of the stack of articles, means for moving said plates toward each other and for moving said panel away from said wall to allow the stack of articles to drop on said plates.

6. In an article retaining and dispensing device, a support including a base, a wall secured to said base, and a frame secured to said base spaced from said wall, means associated with said support for maintaining a plurality of articles and dispensing a selected number thereof, said means including a panel with means yieldingly pressing said panel against some of the articles to hold said some of the articles while at least one other of the articles is being discharged, means for supporting said panel within said frame for vertical adjustment, said panel cooperating with said wall to retain the upper members of a stack of articles, plates pivoted to said base for supporting at least the bottom member of the stack of articles, means for moving said plates toward each other and for moving said panel away from said wall to allow the stack of articles to drop on said plates, and means associated with said last mentioned means for controllably regulating the travel of said panel relative to the movement of said plates.

7. An article dispenser comprising a support having a stationary wall, a substantially parallel movable wall spaced from said stationary wall to form a magazine to support a stack of articles, and means normally urging said movable wall toward said stationary wall and against the stack,

frame members carried by said support and disposed adjacent said movable wall, a spring engaging at least one of said members and said movable wall constantly urging said movable wall toward said base, and means operatively connected with said movable wall for retaining said movable wall slightly spaced from the stack of articles, a pair of plates pivotally mounted on said support and disposed beneath and between said walls to support a stack of articles, means including an actuator attached to said plates for pivotally moving said plates away from each other and for simultaneously releasing said retaining means so that the movable wall engages at least some of the articles of the stack of articles, means operatively engaging said movable wall for raising and lowering said movable wall adjustably to locate the movable wall predetermined distances above the adjacent one of said plates whereby at least the bottom article of a stack is free of clamping engagement with said movable wall.

8. An article dispenser comprising a support having a stationary wall, a substantially parallel movable wall, frame members carried by said support disposed adjacent said movable wall, a spring engaging at least one of said members and said movable wall constantly urging said movable wall toward said base, a pair of plates pivotally mounted on said support and disposed beneath and between said walls to support a stack of articles, an actuator attached to said plates for pivotally moving said plates, means operatively engaging said movable wall for raising and lowering said movable wall adjustably to locate the movable wall predetermined distances above the adjacent of said plates whereby at least the bottom article of a stack is free of clamping engagement with said movable wall, means operatively associated with said movable wall and said actuator for moving said movable wall toward said stationary wall in response to and while said plates are actuated to release at least one article from a stack.

45 9. The combination of claim 8 and said last mentioned means including a spring reacting on said movable wall and at least one of said frame members, a bracket secured to said movable wall and a threaded member carried by said bracket and reacting on said actuator.

10. The combination of claim 6 and said last mentioned means including a bracket secured to said panel, a threaded member mounted on said bracket for axial adjustment and being operatively engaged and motivated by said plate moving means.
